UNITED STATES PATENT OFFICE.

LESLIE M. DARROW, OF STOCKTON, CALIFORNIA, ASSIGNOR OF ONE-HALF
TO BERNARDO GIANELLI, OF SAME PLACE.

IRONING-BOARD.

SPECIFICATION forming part of Letters Patent No. 352,182, dated November 9, 1886.

Application filed March 5, 1886. Serial No. 194,101. (No model.)

To all whom it may concern:

Be it known that I, LESLIE M. DARROW, a citizen of the United States, residing at Stockton, in the county of San Joaquin and State of California, have invented certain new and useful Improvements in Ironing-Boards, of which the following is a specification, reference being had therein to the accompanying drawings.

10 My invention relates to an improvement in that class of domestic appliances termed "laundry implements," upon which clothes are ironed; and it consists in the combination and arrangement of certain parts, as hereinafter explained, and pointed out in the claim.

Referring to the accompanying drawings, Figure 1 is a bottom view of my ironing-board, with part broken away. Fig. 2 is a section through line *x* *x*, Fig. 1. Fig. 3 is a view of 20 the head-piece, which is attached to the wall.

A is the ironing-board proper, which has a tenon at the front end which is inserted in a mortise in a head-piece, B, which is screwed to the wall. Hooks *a* secure the board A to 25 the piece B by means of the staples *b*. Cross cleats C and D, the former at the front end and the latter at the center of the board A, stiffen the board A. A longitudinal cleat, F, extends rearwardly from the cleat D, and is 30 secured to the bottom of the board A. It has upon its face, rigidly attached, an iron plate, H, furnished with screw-holes at certain de-

sired intervals. A brace-leg, E, has one part of a hinge, *e*, screwed to its top. The other part of the hinge *e* is attached by a set-screw, 35 G, (passing through a hole in hinge *e*,) to the plate H at any one of its screw-holes *g*.

The board A being set in position and attached by the hooks *a* and staples *b* to the piece B, attached to the wall, as shown, the 40 brace-leg E is attached to the plate H at any desired point and its lower end pressed firmly against the wall. The ironing-board is then in readiness for use.

When not in use, the board A may be detached from the piece B. 45

Having thus described my invention, what I claim, and desire to secure by Letters Patent, is—

The combination of the board A, the head-piece B, the hooks *a* and their staples *b*, the cross-cleats C and D, the longitudinal cleats F, the plate H, attached thereto and provided with a series of screw-threaded apertures, *g*, the hinge *e*, the set-screw G, and the brace-leg 50 E, substantially as and for the purposes set forth.

In testimony whereof I affix my signature in presence of two witnesses.

LESLIE M. DARROW.
